UNITED STATES PATENT OFFICE.

GEORGE E. MONAHAN, OF CLEVELAND, OHIO.

SHOE-SHINING STAND.

1,286,712.

Specification of Letters Patent.

Patented Dec. 3, 1918.

Application filed January 31, 1918. Serial No. 214,581.

To all whom it may concern:

Be it known that I, GEORGE E. MONAHAN, a citizen of the United States, residing at Cleveland, county of Cuyahoga and State 5 of Ohio, have invented a new and useful Shoe-Shining Stand, of which the following is a specification.

My invention relates to a shoe shining stand which has means to hold the shoe to 10 be shined down upon the stand.

The object of my invention is to provide a stand which holds the shoe upon the stand and which permits of easy and ready clamping of the shoe thereon.

15 I attain this object by the mechanism illustrated in the accompanying drawings which show one embodiment of my invention and in which Figure I is a top plan view of a shoe shining stand, Fig. II is an elevation 20 of Fig. I, and Fig. III is a section on line 3-3 of Figs. I and II.

Similar reference characters refer to similar parts throughout the views.

The body 1 made of suitable material and, 25 preferably, ribbed as shown for the purpose of economic production as to weight, has the flat surface 2 upon which the sole of the shoe rests, and further has the cut away portion 4 upon which the heel rests, and further has 30 the flanges 5 for the purpose of clamping the stand down upon a suitable support. On the central rib 6 and near the central part of the body, the bosses 7 are provided. The stud 8 passes through the bosses 7 and may, 35 conveniently, be secured therein while casting the body 1 although it is preferred that the stud 8 fits loosely in the bosses 7. The faces 9 of the bosses 7 are concave. It is not necessary that these faces 9 be machined 40 since this concave surface can readily be provided while casting the body 1. Adjacent to the bosses 7, the rib 6 is provided with a notch 10 to receive the spring 11 as will appear hereinafter.

45 Each clamp arm 12 has the hook 13, both of which are adapted to grip the sole of a shoe, preferably at or near the arch.

It is noted that these hooks 13 are somewhat broad for the purpose of taking hold 50 of a comparatively large portion of the shoe sole to the end that the sole may not be injured as will be done by narrow hooks. At the proper location, each clamp arm 12 has the boss 14, the front faces of which are convex to correspond and fit to the concave faces 55 9 on the bosses 7. The bosses 14 have the

openings 15 which are somewhat larger in diameter than the studs 8, and further have the countersinks 16 to receive the nuts 17. The clamp arms 12 further have the lugs 60 18 which have the openings 19 which receive the ends of the spring 11.

It will be seen that the clamp arms 12 are flexibly mounted on the body 1; the concave and convex surfaces 9 forming a ball 65 joint which permits the clamp arms to swivel in any direction so that the hooks 13 can adjust themselves to the outline or contour of the shoe sole and, at the same time, permit of the manipulation of the 70 clamp arms to readily grip or release the shoe.

The spring 11, made of suitable strength and material, has the circular coil 20; the point 21 resting against the upper rear surface of the notch 10 while the point 22 rests against the lower front surface of the notch 10; the ends 23 of the spring 11 pass through the openings 19 in the ends of the clamp 75 arms 12.

80 The operation of the stand described is as follows:

When the stand is not in use, the clamp arms 12 may assume the position shown in dotted lines in Fig. II. A shoe is then 85 placed upon the body 1 and may rest on the faces 2 and 4. The ends of the clamp arms 12 (near lugs 18) are then pressed inwardly or toward each other which may be done with one hand, whereupon the points 13 of 90 the arms 12 are removed a short distance from the body 1 and the legs of the spring 11 are somewhat compressed thereby or put under more tension than when in normal position, although the spring 11 should be 95 under some tension when the arms are in the position shown dotted in Fig. II. These same ends of the arms 12 are then pushed downwardly, which may be done with the same hand mentioned until the points 13 are 100 brought a short distance above the top of the shoe sole. These same ends of the arms 12 are then released whereupon the points 13 move inwardly and downwardly and grip the shoe sole automatically and force the 105 shoe down upon the body. The concave surfaces on the bosses 7 and the convex surfaces on the bosses 14 and the openings 15 and 16 which are larger than the parts that enter therein, being provided to permit the 110 arms 12 to move or swivel in all directions so that the points 13 may adapt themselves

to different sizes and styles of shoes. These movements are accomplished by the arrangement and method of attaching the spring 11, which is as follows: When the arms 12 are in position shown dotted in Fig. II, there is practically no tension on the spring 11 longitudinally, but the points 21 and 22 rest rather heavily on the corresponding surfaces of the notch 10. There is, however, considerable tension on the spring 11 transversely, which tension tends to force the outer end of the arms 12 (near lugs 18) away from each other. Now, when these outer ends of the arms 12 are pushed down, whereupon the points 13 move upwardly, considerable tension is imposed upon the spring 11 longitudinally owing to the points of suspension at 18, 21, and 22. When the hand is released from these outer ends of the arms 12, this tension of the spring 11 tends to force these outer ends of the arms 12 upwardly and consequently tends to force the points 13, which have gripped the shoe sole, downwardly, whereby the shoe will be held upon the stand by the tension of the spring 11. In order to release the shoe, it is only necessary to press the outer ends of the arms 12 inwardly or toward each other sufficiently far so that the points 13 clear the shoe sole, whereupon the tension of the spring 11 will force the points 13 downwardly and the shoe is released.

It will be seen that this invention provides a stand which is economical of manufacture since very little machine work is required and all parts are so designed that a good clean casting may be made without any cores.

Even the concave and convex surfaces may be cast smooth since the mold can be parted in such a way that no seam appears on these surfaces. It will further be seen that this invention provides a stand which is efficient since a slight movement of one hand releases or grips and holds the shoe in position. No part of the stand projects outside of the shoe and no nuts or other projections appear outside of the apparatus proper so that a shoe brush or polishing cloth may freely be used in the usual manner without danger of injury to either brush or cloth.

I am aware that various modifications are possible within the scope of my invention.

Therefore, without limiting myself to the precise construction shown, I claim:

1. An apparatus of the character described comprising a body, a pair of clamp arms attached to the body by ball joints and provided with inwardly directed jaws, and a spring held against movement in the body and adapted to force the outer ends of the clamp arms outward and upward to hold an object down upon the body.

2. An apparatus of the character described comprising a body, a clamp arm mounted on each side of the body by a ball joint and provided with an inwardly directed jaw, a spring held in the body and having its ends attached to the outer ends of the clamp arms, the clamp arms adapted to adjust themselves to the contour of the object to be held, and the spring adapted to force the outer ends of the clamp arms outward and upward to hold the object down upon the body.

GEORGE E. MONAHAN.
